CONCRETE SLAB MAKING MACHINE

Cole Y. Strong, Denver, Colo., assignor to Consolidated Industries, Inc., Denver, Colo., a corporation of Colorado

Filed Dec. 24, 1962, Ser. No. 246,728
3 Claims. (Cl. 25—41)

This invention pertains to concrete slab making machines and particularly to a machine adapted to make concrete slabs for forming grave vaults and the like.

One of the objects of this invention is to provide an automatic machine for making concrete slabs.

Another object of this invention is to provide a machine for automatically forming a series of concrete slabs, one on top of the other to form a sandwich-like pile on a pallet for handling and storage.

A further object is to provide a concrete slab making machine capable of forming a plurality of accurately dimensioned slabs vertically sandwiched one on top of the other to a desired height and number as required.

It is also an object to provide apparatus for forming sandwiched stacks of concrete slabs incorporating reinforcing mesh intermediate the thickness of the slabs.

A further object of this invention is to provide a machine for automatically forming a series of horizontally stacked concrete slabs which can be varied in size and shape configuration to suit the product which is to be utilized.

Further features and advantages of this invention will appear from a detailed description of the drawings in which:

FIG. 1 is a plan view of a concrete slab making machine incorporating the features of this invention.

FIG. 2 is a side elevation of the concrete slab making machine shown in FIG. 1.

FIG. 3 is a vertical longitudinal sectional view on the line 3—3 of FIG. 1.

FIG. 4 is a vertical transverse sectional view on the line 4—4 of FIG. 1.

FIG. 5 is a fragmentary diagrammatic view showing the initial forming of a concrete slab on a pallet by the machine.

FIG. 6 is a fragmentary diagrammatic view similar to FIG. 5 but showing the completion of the formation of the stack of concrete slabs.

FIG. 7 is an enlarged sectional view on the line 7—7 of FIG. 4.

FIG. 8 is an enlarged sectional view on the line 8—8 of FIG. 7.

FIG. 9 is a circuit diagram of the operating and control mechanism of the machine.

As an example of one embodiment of this invention, there is shown a concrete slab making machine comprising a main support 14, a plurality of rectangularly spaced vertical columns 15 having floor flanges 16 rigidly fixed thereto and rigidly bolted to the surface 17 of a suitable floor 18 by the bolts 19, as best seen in FIGS. 1, 2 and 7. Guide tubes 20 are vertically slidable on each of the columns 15 and are rigidly connected by the support blocks 21 to the vertical corner members 22 of the frame 23 which includes the end tie bars 24 fixed to the tops of the vertical corner members 22 and the longitudinal upper tie bars 25 interconnected rigidly between the end tie bars 24. Near the lower ends of the vertical corner members 22 are fixed the lower end tie bars 26 and to which are fixed the lower side tie bars 27, FIGS. 3 and 4. The frame 23 is caused to maintain parallelism of up and down level movement on the columns 15 by apparatus comprising a pair of horizontally disposed shafts 28, which are interconnected for synchronous rotation by a chain 28a operating over sprockets 29a fixed to the shafts 28, FIGS. 1 and 4, suit-

2

ably journaled in bearings 29 on top of the columns 15. Sprockets 30 are fixed to the shafts 28 at the top of the columns 15 over which operate the leveling chains 31, one end 32 of which chains are suitably dead ended or fixed by a suitable bolt 33 to integral lugs 34 of the guide tubes 20. The other ends 38 of the chains 31 pass over idler sprockets 35 journaled on suitable pins 36 carried in slots 37 in the bottom of the columns 15 and are connected or dead-ended by bolts 39 to the integral lugs 34a of the guide tubes 20. By this arrangement the frame 23 may move up and down on the columns 15 while maintaining exact parallelism with the floor surface 17.

The frame 23 may be locked in any vertical position on the columns 15 by fluid pressure actuated brakes 40, best shown in FIGS. 7 and 8, located on the lower ends of the tubes 20 comprising the integral brake sleeve 41 having the enlarged counterbore 42 in which are retained the brake shoe segments 43 and 44 and confined therein by the flange 45 held in place by the bolts 46 passing through the integral flange 47 of the guide tube 20, the shoes 43 and 44 having axial end clearance between the surface 48 of the counterbore 42 and the surface 49 of the flange 45 so that slight radial movements of the shoes relative to the counterbore 42 and the surface 50 of the columns is present. An actuating plunger 51 is axially slidable in the radially disposed bore 52 with its inner end 53 engaging the outer diameter 54 of the brake shoe segment 43. A fluid pressure chamber 55 is formed in the bore 52 behind the plunger 51 to which is connected suitable fluid pressure supply lines 56 so that when pressure is applied in chamber 55 behind the plunger 51 the brake shoes 43 and 44 will be clamped to the columns 15 to hold the frame 23 in desired vertical position on the columns 15.

Rigidly fixed to and depending downwardly from the lower side tie bars 27 is the mold box 57 having the sides 58 and the ends 59 having the hinged lower portions 60 hinged at 61, FIGS. 2, 3, 4 and 6, to the lower edges of the ends 59. Suitable releasable clamps 62 interconnected between the sides 58 and the hinged ends 60 serve as releasable means to secure the hinged ends in downwardly swung vertical closed position with the mold box sides 58.

Fixed to the frame 23 and to the mold box ends 59 are the feed drawer platforms 63 and 64 each having a suitable support frame 65 to which is fixed the deck plates 66 and 67, FIGS. 3 and 5, located in the plane 68 of the top edges of the sides 58 and ends 59 of the mold box 57. Adapted to slide back and forth between the deck plates 66 and 67 across the top edges 68 of the mold box 57 is the feed drawer 69 consisting of an open bottomed box having the sides 70 and the ends 71 and 72. The bottom edges 73 of the sides 70 and ends slide across the top of the deck plates 66 and 67 and the top edges 68 of the mold box. Suitable guide clips 74 fixed to the sides 70 of the feed drawer and engaging the side edges of the deck plates 66 and 67 and the sides 58 of the mold box serve to maintain lateral alignment of the feed drawer over the deck plates and mold box during its longitudinal sliding movements.

The feed drawer 69 is reciprocated by fluid pressure by a suitable fluid pressure cylinder 75 carried on the frame 23 on one side of the upper portion of the mold box 57 having a piston rod 76 extending out both ends of the cylinder, FIGS. 1, 2, 4 and 9, to which are connected the chains 77 and 78. The chain 77 passes over an idler sprocket 79 journaled on a suitable stud 80 carried in the support bracket 81 fixed to a vertical corner member 22 of the frame 23. The other chain 78 operates over a sprocket 82 fixed to a drive shaft 83 journaled in a bracket 84 fixed to a vertical corner member 22 of the frame 23. The outer ends 85 and 86 of the respective chains 77 and 78 are interconnected by the link 87.

Fixed on the drive shaft 83 is the sprocket 88 over which operates the chain 89 which in turn operates over the sprocket 90 fixed to the shaft 91 journaled in the frame 65 of the deck plate 67. The shaft 91 extends out each side of the frame 65 and has fixed thereon the sprockets 92 over which operate the endless feed drawer chains 93. The other ends of the chains 93 are carried on sprockets 94 fixed on the ends of a shaft 95 journaled in the frame 65 of the deck plate 66. Suitable clamp devices 96 fixed to the sides 70 of the feed drawer 69 are adapted to grip the upper span of the endless chains 93. The cylinder 75 is energized from a suitable source of fluid pressure such as the fluid pressure pump 97, FIG. 9, having a suction line 98 connected to a reservoir 99 of fluid 100. High pressure discharge from the pump 97 passes through pressure line 101 into a suitable accumulator 102. Discharge from the accumulator 102 passes through pressure supply line 103 which is connected to the feed drawer control valve 104 having a return drain line 105 connected into the reservoir 99. The control valve 104 is connected by lines 106 and 107 to the cylinder 75 so that by manipulating the control valve handle 108 of the valve 104, the piston rod 76 may be reciprocated and through the connected transmission, the feed box reciprocates as required during the operation of the machine.

A pressure plate 109 is mounted for vertical relative movement on the frame 23. The pressure plate 109 has edges 110 which are arranged to fit closely within the interior surfaces of the sides 58 and ends 59-60 of the mold box 57. The pressure plate 109 is fixed to the lower ends 111 of the piston rods 112 of the vertically disposed fluid pressure cylinders 113, FIGS. 1, 2, 4 and 9, which have their upper ends 114 pivotally connected to a shaft 115 which is fixed in the brackets 116 fixed to the upper tie bars 25 of the frame 23.

In order to maintain exact parallelism of the bottom surface 117 of the pressure plate 109 with the plane 68 of the top edges of the mold box 57 and the floor surface 17 when the cylinders 113 are energized to vertically relatively move the pressure plate 109 and the frame 23, there is provided the links 118 which are pivotally connected at their upper ends by pins 119 carried in suitable brackets 120 fixed to the outside faces of the upper tie bars 25 of the frame 23. The lower end of the links 118 are pivotally connected by a pin 121 to the outer ends of lever arms 122 fixed to the outer ends of the shafts 123 which are journaled in suitable brackets 124 fixed to the upright supports 125 in turn fixed at their lower ends to the supporting frame 126 fixed to the top surface 127 of and adjacent the edges 110 of the pressure plate 109. The shafts 123 are interconnected for synchronized angular rotation by endless crossed chains 128 operating over identical sprockets 129 fixed adjacent the brackets 124 on shafts 123. Laterally spaced links 130 straddle the chain 128 and interconnect the ends 131 of the chains 128.

Longitudinal horizontal positioning of the pressure plate 109 is maintained by rollers 132 journaled on pins 133 carried on frame members 134 fixed at their inner ends to the upright supports 125 and near their outer ends to tie pieces 135 fixed at their lower ends to the support frame 126 of the pressure plate 109, the roller 132 riding up and down against the surfaces 136 of the vertical corner members 22, FIGS. 2 and 3. Lateral horizontal positioning of the pressure plate 109 is maintained by the rollers 137, FIG. 4, journaled on pins 138 fixed in the outer ends of the members 139 fixed transversely on the outer ends of the frame members 134, the rollers 137 riding up and down against the surfaces 140 of the vertical corner members 22.

The relative vertical movement of the frame 23 and the pressure plate 109 is limited by the rods 141 which are fixed at their lower ends to the frame member 134 which pass up through clearance holes 142, FIGS. 3 and 4, in stop bars 143 fixed to the upper tie bars 25 by suitable brackets 144. The upper ends of the rod 141 are

threaded and have suitable adjustable thrust nuts and washers 145 adapted to engage the top surface 146 of the stop bars 143 to limit the downward relative position of the pressure plate to the frame 23. The upward relative position of the pressure plate is determined by the bottoming of the pistons 147 in upper position in the cylinders 113. A suitable vibration such as by means of the electric motor driving the vibrator shaft 149 through the belt 150 and through the belt 151 to the vibrator shaft 152 may be employed on the top surface 127 of the pressure plate 109. The details of the vibrator construction forming no part of the present invention will not be described in further detail as any suitable commercially available vibration will suffice.

The operation of the cylinders 113 is controlled by the reversing valve 153, FIG. 9, which receives a pressure supply from the line 103 and has a return drain line 154 to the reservoir 99. The top chambers 155 of the cylinders 113 are connected by the common line 156 to the control valve 153 while the lower chambers 157 of the cylinders 113 are connected by the common line 158 to the control valve 153 so that by manipulating the control valve handle 159 the cylinders can be energized to raise and lower the pressure plate 109 relative to the frame 23.

A master brake cylinder 160, FIG. 9, has a fluid pressure chamber 161 which is connected to the line 156 through line 162, shut off valve 163 and line 164. A piston 165 in the master cylinder 160 is normally yieldingly urged by a compression spring 166 to oppose pressure in the pressure chamber 161. A piston rod plunger 167 fixed to the piston 165 extends through the pressure chamber and outwardly through a sealed bore 168 and projects into the brake fluid chamber 169 which chamber 169 is connected through a common line 170 to the brake cylinder pressure chambers 55, FIG. 8. A hand pump 171 having an operating handle 172 is connected through a line 173, check valve 174 and line 175 to the pressure chamber for initially charging the chamber 169 with brake fluid so that the spring 166 acting through the piston 165 and plunger 167 applies the proper pressure in the chamber 169 to set the brakes 40 for locking the frame 23 to the columns 15. A suitable gage 176 in line 170 indicates if proper braking pressure is being maintained in the braking circuit 170.

A pallet cart 177 has a lower frame comprising the integrally connected end members 178 and side members 179 having upright corner posts 180, FIGS. 3 and 4. Ground contacting wheels 181 rolling on the floor surface 17, are journaled against axial movement on suitable transverse shafts 182 fixed in the side members 178 of the pallet cart. A pallet support structure comprising the cross members 183 and the extended side members 184 are fixed to the tops of the upright corner posts 180 to form a horizontal surface 185 parallel to the floor surface 17 and the bottom surface 117 of the pressure plate 109. A stack carrying pallet 186 having a top work receiving surface 187 parallel to the surface 117 of the pressure plate 109 is carried on the pallet cart 177.

In operation: With the frame 23 and moldbox 57 in lowered position clamped to the column 15 by brakes 40, a hinged end 60 is swung up and the pallet cart 177 with a pallet 186 is moved into the mold box 57 as shown in FIGS. 3, 4 and 5. The sides 188 and ends 189 of the pallet 186 just nicely fit with close clearance within confines of the inside walls of sides 58 and ends 60 of the moldbox 57. The hinged end 60 that has been open up to accommodate the pallet cart 177 and pallet 186 is swung back down and locked in operative position by the clamps 62. At this time control lever 159 of valve 153 has been moved to a position to apply pressure in the line 158 to pressure chambers of cylinders 113 to hold the pressure plate 109 in raised position shown in FIGS. 2 and 3. Also, at this time spring 166, FIG. 9, in master brake cylinder 160 has push piston 165 and plunger 167 into brake fluid chamber 169 setting the brakes 40. Lever

103 of control valve 104 is moved to a position to energize cylinder 75 to position the feed drawer 69 on the deck plate 66.

Control lever 159 of valve 153, FIG. 9, is then manipulated to apply pressure in the line 156 into chambers 155 of the cylinders 113 causing pressure plate 109 to move down into the mold box to engage the pallet surface 187 when its downward movement is stopped. Pressure in line 156 then builds up and is transmitted through line 164, valve 163 which is normally left open, the line 162 into pressure chamber 161 of the master brake cylinder 160 pushing piston 165 and plunger 167 to the left against spring 166 relieving pressure in chamber 169 to release the brakes 40.

With the release of the brakes 40 and continued pressure in the chambers 155 of cylinders 113 and pressure plate 109 supported on the pallet 186, the frame 23 is caused to move upwardly on the columns 15 until the thrust nuts and washers 145 engage the top surface 146 of the stop bars 143 of the frame 23, FIG. 4. The position of stopping is such that the distance between the top surface 187 of the pallet 186 and the bottom surface 117 of the pressure plate equal the desired depth of material to be deposited within the mold box 57 for each slab to be formed.

Control lever 159 of valve 153 is then moved to release pressure from line 156, which allows brakes 40 to set holding the frame 23 to the columns 15 and to apply pressure in line 158 to raise the pressure plate to up position, FIGS. 2 and 3, for movement of the feed drawer 69 across the mold box.

A suitable supply of plastic concrete is placed in the feed drawer 69 positioned on the deck plate 66, FIG. 5, and control lever 103 of control valve 104, FIG. 9, is operated to cause the loaded feed drawer 69 to move across the top of the mold box 57 to the deck plate 67 dumping a supply of plastic concrete therein. The control lever 103 is then moved to bring the feed drawer 69 back to the deck 66, screeding off the supply of concrete to the height of the mold box ready for the compacting operation.

The control lever 159 of valve 153 is then operated to apply pressure in line 156 to cause pressure plate 109 to move down against the screeded surface of the plastic cement and into the mold box to compact the supply of cement therein until the pressure in line 156 builds up to a predetermined point whereupon the brakes 40 are released causing the frame 23 to move upwardly the desired thickness of the next slab at the point where the thrust washers and nuts 145 engage the stop bars 143. Lever 159 of valve 153 is then moved to release pressure in line 156, causing brake 40 to set to hold frame 23 position and to apply pressure in line 158 to raise the pressure plate 109 to up position.

A layer of suitable parting paper or parting sand 191 is then placed on the top surface of the slab 192 in the mold box that has just been formed. The feed drawer is then moved over the mold box placing the next charge of plastic concrete therein and the above described operations repeated until a stack of sandwiched slabs 193 to 198a inclusive, FIG. 6, have been completed, the frame 23 and mold box 57 moving progressively upwardly for each slab formed. When all of the required slabs have been completed, a hinged side 60 is swung open and the pallet cart with the pallet 186 containing the stack of finished slabs thereon is rolled out of the mold box ready for curing and storage.

In certain instances it may be desirable to insert reinforcing mesh or rod 199 intermediate the top 200 and bottom 201 surface of a slab 192-198a. To this end there is provided a flipper screed bar 202, FIG. 5 hinged at 203 at the bottom edge of the end 71 of the feed drawer, the width of the screed bar 202 equaling substantially one half the slab to be formed. When the feed drawer 69 is on the deck plate 66 the screed bar 202 is swung

up to horizontal position lying on top of the deck 66. As the feed drawer 69 moves off of the deck 66 over the mold box 57 the screed bar 202 drops to a vertical position so as to screed the material in the mold box 57 to half its normal depth, the feed drawer continuing until it moves out over the opposite deck 67 with the screed bar 202 stopping at the edge 204 of the mold box. Before the feed drawer starts back, mesh or reinforcing rods are laid on the concrete just deposited in the mold box. The feed drawer then moves back across the mold box causing the screed bar 202 to flip up to horizontal position as it comes up over the edge 205 of the mold box, the edge 206 of the mold box 69 screeding further material over the reinforcing to full depth in the mold box to complete the loading thereof for the application of forming pressure by the pressure plate 109. If desired, the above described operation of the screed bar 202 may be affected by suitable cam lever mechanism, not shown, operating in response to the position and movement of the feed drawer.

There has thus been provided a procedure and apparatus in which a pallet 186 is surrounded by a vertically movable mold box 57, in the present example, of rectangular configuration closely fitting around the edges 25 of the pallet 186. A feed drawer 69 traversing across the top edge 68 of the mold box distributes a concrete mixture 190 of suitable consistency, preferably dry-mix of low water content, into the mold box area above the pallet 186 and screeds the concrete off level with the top edge 68 of the mold box extending above the pallet 186. A pressure plate 109 then presses down on the top of the deposited concrete mixture which is preferably vibrated until a certain degree of settlement, approximately 20%, takes place. Following this, further pressure is applied 30 downwardly on the pressure plate 109 which then causes the frame 23 and the attached mold box around the just cast slab 192 to move upwardly to a new location equal to the thickness plus the compaction settlement of the next slab 193 to be cast on top of the already cast slab 192. At this point the frame 23 is automatically locked 35 by the brakes 40 to the supporting columns 15 on the floor surface 17 upon which is carried the pallet cart 177 supporting the pallet 186 and the slab 192-198 being formed. The brakes 40 hold the frame in its raised position 40 so that the new position of the mold box 57 and its top edge above the previously cast slab 192 is maintained. A piece of foil, water impervious paper or parting sand 191 is placed on top of the just cast slab 192 and then the feed drawer is again moved over the mold box and 45 previously cast slab to repeat the above described operating cycle. The above operation continues for the number of slabs 192-198a vertically sandwiched one on top of the other to the desired height and number in a stack as required.

50 While the apparatus herein disclosed and described constitutes a preferred form of the invention, it is also to be understood that the apparatus is capable of mechanical alteration without departing from the spirit of the invention and that such mechanical arrangement and commercial adaptation a fall within the scope of the appended claims are intended to be included herein.

Having thus fully set forth and described this invention what is claimed and desired to be obtained by United States Letters patent is:

- 60 1. A concrete slab making machine comprising in combination:
- a main support fixed to a floor surface,
  - a frame vertically movable on said main support relative to said floor surface,
  - releasable locking means on said frame for locking said frame against vertical movement on said main support,
  - a pallet cart supported on said floor surface,
  - a pallet carried on said cart,

- (f) a mold box fixed on said frame adapted to receive said pallet,
- (g) deck plates fixed on said frame and located at opposite ends of said mold box,
- (h) a feed drawer supported on said deck plates and said mold box adapted to move back and forth across the top of said mold box from deck plate to deck plate,
- (i) power means on said frame for actuating said feed drawer in said back and forth movements,
- (j) a pressure plate mounted for vertical relative movement on said frame into and out of said mold box,
- (k) power means interconnected between said frame and said pressure plate adapted to relatively vertically reciprocate said pressure plate and said frame,
- (l) stop means on said pressure plate adapted to engage said frame to limit upward relative travel of said frame relative to said pressure plate,
- (m) means actuated by restraining the downward movement of said pressure plate to release said locking means to cause upward movement of said frame relative to said pressure plate.

2. A concrete slab making machine comprising in combination:

- (a) a main support fixed to a floor surface,
- (b) a frame vertically movable on said main support relative to said floor surface,
- (c) releasable locking means on said frame for locking said frame against vertical movement on said main support,
- (d) a pallet cart supported on said floor surface,
- (e) a pallet carried on said cart,
- (f) a mold box fixed on said frame adapted to receive said pallet,
- (g) deck plates fixed on said frame and located at opposite ends of said mold box,
- (h) a feed drawer supported on said deck plates and said mold box adapted to move back and forth across the top of said mold box from deck plate to deck plate,
- (i) power means on said frame for actuating said feed drawer in said back and forth movements,
- (j) a pressure mounted for vertical relative movement on said frame into and out of said mold box,
- (k) power means interconnected between said frame and said pressure plate adapted to relatively vertically reciprocate said pressure plate and said frame,
- (l) stop means on said pressure plate adapted to engage said frame to limit upward relative travel of said frame relative to said pressure plate,
- (m) means actuated by restraining the downward movement of said pressure plate to release said locking means to cause upward movement of said frame relative to said pressure plate.

3. A concrete slab making machine comprising in combination:
- (a) a main support fixed to a floor surface,
  - (b) a frame vertically movable on said main support relative to said floor surface,
  - (c) releasable locking means on said frame for locking said frame against vertical movement on said main support,
  - (d) a pallet cart supported on said floor surface,
  - (e) a pallet carried on said cart,
  - (f) a mold box fixed on said frame adapted to receive said pallet,
  - (g) deck plates fixed on said frame and located at opposite ends of said mold box,
  - (h) a feed drawer supported on said deck plates and said mold box adapted to move back and forth across the top of said mold box from deck plate to deck plate,
  - (i) power means on said frame for actuating said feed drawer in said back and forth movements,
  - (j) a pressure plate mounted for vertical relative movement on said frame into and out of said mold box,
  - (k) power means interconnected between said frame and said pressure plate adapted to relatively vertically reciprocate said pressure plate and said frame,
  - (l) stop means on said pressure plate adapted to engage said frame to limit upward relative travel of said frame relative to said pressure plate,
  - (m) means actuated by restraining the downward movement of said pressure plate to release said locking means to cause upward movement of said frame relative to said pressure plate,
  - (n) and further means adapted to normally hold said locking means in locked condition when said power means for reciprocating said pressure plate is moving said pressure plate unimpeded in downward and upward vertical movement relative to said frame.
